FIELD HOSPITAL BED

Benjamin D. Pile, 50-20 213th St.,
Bayside, N.Y. 11364
Filed July 7, 1966, Ser. No. 564,510
6 Claims. (Cl. 5-111)

ABSTRACT OF THE DISCLOSURE

This invention relates to collapsible structures, and particularly to those of a foldable nature such as a field cot or a bed.

The structure collapses by removing each leg from its individual mounting and folding at the hinged center. The legs are not loose, but are carried by longitudinal tension supports which extend parallel to the long axis of the frame from opposite leg mounting sleeves. The particular utility stems from the compact nature of the collapsed structure due to the absence of bulky leg hinges coupled with the stability when assembled necessary for a field hospital bed due to the tension support members which act on the frame through the legs and leg mounting sleeves.

The invention described herein may be manufactured and used by or for the Government for governmental purposes without the payment to me of any royalty thereon.

CROSS REFERENCE TO RELATED APPLICATION

The cot or bed of this invention, when assembled is particularly durable and therefore useful in military installations such as field hospitals. This invention achieves stability through the use of a longitudinal tension support similar to that disclosed in my prior U.S. Patent No. 3,037,215.

BACKGROUND OF THE INVENTION

1. Field of the invention

This invention pertains to collapsible frames for use in portable beds and cots. The invention includes also an embodiment having elevated sections at either end for the head and feet of a patient, and mounting sleeves for trays and article supports which may be releasably mounted on the frame.

2. Description of the prior art

The operation of a field hospital requires a stable portable bed. The stability required must be combined with a structure which folds into a compact unit for storage and transportation. Although the longitudinal tension member utilized in this invention for the required stable assembly is known, the prior art describes no device with the required stability which is foldable into a compact package.

SUMMARY

The frame of this invention may be used in either a cot or a bed.

The compact nature of the collapsed cot or bed makes it readily transportable and efficient for storage purposes. This particular utility stems from a unique feature whereby each leg of said structure is separable from its mounting sleeve, but fixed to the tension support in such a manner that no hinge connections are needed between the legs and the frame. This feature allows the folding of the structure to a thickness of about three to three and one half inches without the disadvantage of separate legs, easily lost during transportation.

Accordingly, it is an object of this invention to provide a collapsible structure having a longitudinal tension mem-

2

ber, and legs carried by said member but separable from the frame.

It is also an object to provide a rectangular, collapsible structure having a longitudinal tension support which acts with both a longitudinal and transverse component, and coacts with the legs at the corners thereof when the legs are mounted, but releases when the legs are dismounted.

It is a further object to provide a collapsible frame structure having compact features when in a collapsed condition, but capable of functioning as a standard hospital bed to include an elevation capability at either the head or the foot or both.

BRIEF DESCRIPTION OF THE DRAWINGS

These and other objects will become readily apparent with reference to the drawings and following description wherein:

FIG. 1 is a perspective view of the frame of this invention functioning as a cot;

FIG. 2 is a partial cross-sectional view along line 2-2 of FIG. 1;

FIG. 3 is a cross-sectional view along line 3-3 of FIG. 1;

FIG. 4 is a perspective view of the frame of this invention adapted for use as a hospital bed;

FIG. 5 is a cut-away view of the locking mechanism along line 5-5 of FIG. 4;

FIG. 6 is an alternate locking mechanism;

FIG. 7 is a top view of the bed of FIG. 4 partially cut away to show the alternate legs for the tray, and the disposition of optional sleeves for holding the tray or a utility support;

FIG. 8 is a cut-away view of the tray taken along line 8-8 of FIG. 7; and

FIG. 9 shows the structure folded.

DESCRIPTION OF THE PREFERRED EMBODIMENTS

The structure of this invention consists of a frame, 1, having sleeves, 2, disposed in the corners thereof and adapted to receive the legs, 3. A longitudinal tension support, 4, which preferably is a $\frac{5}{32}$ inch cable, extends through a sleeve, 2, at either end of the structure, and terminates in a ball, 5, which closes the upper end of the sleeve, 2, to maintain the cable in a fixed position.

The legs, 3, are slidably received in the sleeve, 2, for mounting. The tension support, 4, extends from hole, 6, through the end portion of the leg, 3. In this manner the leg, 3, may be withdrawn from the sleeve, 2, but remains attached to the structure and carried by support, 4.

The frame, 1, has folding hinges, 7, and may be assembled when unfolded by inserting the legs, 3, in sleeves, 2. The position of hole, 6, in leg, 3, is related to the slack in tension support, 4, so that when leg, 3, is inserted in sleeve, 2, support, 4, is in tension exerting a vertical force against leg, 3, urging it into sleeve, 2, and a horizontal force bowing said frame, 1, to counterbalance any load.

The hinges, 7, are further supported transversely by a central support member, 8. Member, 8, has a recess, 9, in either side. Recess, 9, may receive a ball, 10, attached to tension support, 4, or the connection may be made in any other suitable manner. However, for maximum efficiency the sides, 11, of central support member, 8, should form a 45 degree angle with the horizontal, and extend between the hinge, 7, and tension support, 4.

For greater stability legs, 3, are angled outwardly from a point, 12, located below hole, 6. It should be noted however that the angle should not exceed a few degrees due to the fact that base, 13, should not extend beyond the outer edge of the frame, 1. If base, 13, does extend

beyond the edge of frame, 1, the possibility exists of tripping people working around the structure.

The basic collapsible structure described above may be used with a variety of functional attachments.

To utilize the structure as a hospital bed the following suggested modifications may be incorporated without changing the basic nature of the structure.

An inner frame, 20, may be mounted within the leg-carrying outer frame, 1. Preferably the inner frame should have hinges, 21, as shown in an exposed section of FIG. 4 for elevation of either the head or the foot of the bed. The inner frame, 20, carries the mattress, 24, which may be inflatable.

For elevation a channel, 22, may be removably attached to the inner frame, 20, in any suitable manner such as a combined staple and latch. The channel, 22, may be bent to describe a sector of a circle having as its radius the distance from hinge, 21, to the channel connection, 23. To provide for a maximum of storage space under the bed when the frame is horizontal a few inches of channel, 22, adjacent the connection, 23, may have a slightly greater curvature.

FIGS. 5 and 6 illustrate alternate channel locking assemblies, 27, 27', respectively. In FIG. 5 a friction cam, 29, having a lever, 30, is attached to the frame, 1, and disposed within channel, 22, and may be frictionally seated therein. Clockwise rotation of cam, 29, about pin, 28, as shown in phantom frees channel, 22, for elevation or depression.

In FIG. 6, cam 29' carries a pin, 32, for engaging holes, 33, in channel, 22. The locking mechanism functions as pin 32 is extended through hole, 33, by counter clockwise motion of cam, 29'. The pin then rests on stop, 34, carried by frame, 1.

For proper elevation channel, 22, should be long enough to allow a 70 degree elevation of an end of inner frame, 20, about its hinges, 21.

In addition, to prevent an over extension of channel, 22, a stop notch, 35, may be incorporated at the end of said channel opposite staple, 23. An L-shaped member, 36, is rotatably attached to frame, 1, and allowed to ride on channel, 22. The L-shaped member, 36, will then contact notch, 35, when maximum elevation is reached and prevent the involuntary disconnection of channel, 22, from locking mechanism, 27. Channel, 22, may be disconnected by manually rotating member, 36, away from notch, 35.

Utility sleeves, 40, may be mounted internally to frame, 1, as shown in FIG. 7. Sleeves, 40, may hold a T-support, 41, for mosquito netting, or a hook support, 42, as shown in FIG. 4.

Sleeves, 40, may also be used to mount tray, 50, on frame, 1. As shown in FIG. 8, tray, 50, has two L-shaped legs, 51, rotatably mounted to the tray, and two T-shaped legs, 52. Each L-leg, 51, extending through the cross-member of a T-leg, 52, and rotatably carrying said leg. Stop, 53, on leg, 52, regulates the height of the tray, 50, with relation to frame, 1, when leg, 52, is inserted in sleeve, 40. When a lower tray is needed leg, 52, is rotated into catch, 55, leaving leg, 51, in position to support the tray, 50, when inserted into a sleeve, 40. Tray, 50, may occupy a variety of positions on the frame depending on the placement of sleeves, 40. Holes 40' may be drilled at appropriate places on frame 1 to be used with sleeves, 40, to mount the above described tray and supports. FIG. 7 illustrates a preferred embodiment which would allow tray mounting on either the end of frame, 1, either side, or transversely thereto.

To collapse the bed, the tray, 50, and utility supports, 41 and 42, are removed. Channel, 22, is disengaged from lock mechanism, 27, by raising the end of inner frame, 20, disengaging stop, 36, from notch, 35, and rotating the end of frame, 20, about hinge, 21, until channel, 22, is free. The channel is then disengaged from frame, 20, by releasing staple, 23.

Legs, 3, are then pulled from sleeves, 2. Legs, 3, may have an optional brace, 60, which is rotatably connected to each leg. The brace, 60, should be releasably connected to frame, 1, however so that legs, 3, may be carried only by support, 4.

Frame, 1, may then be folded and the legs, 3, channels, 22, utility supports, 41 and 42, and tray, 50, packed within the folded frame. In a collapsed form the bed is from 3 to 3½ inches thick and weighs about 26 pounds, depending on the number of accessories used and whether the frames, 1 and 20, are tubular steel or not.

A field cot utilizing the structure of this invention would consist only of a frame, 1, sleeves, 2, legs, 3, tension support, 4, and central support member, 8. Frame, 1, carries the mattress, 24, as shown in FIG. 1.

A wide variety of variations and modifications may be employed in the structure of this invention without departing from the basic concept thereof. Accordingly, the invention is not intended to be limited to the specific design herein described, but it is intended to include all mechanical equivalents obvious to one skilled in the art.

I claim:

1. A collapsible support structure comprising:
  - (a) a rectangular, foldable, main frame;
  - (b) a downwardly opening sleeve disposed in each corner of said frame and affixed thereto, for receiving leg members;
  - (c) a leg member having an upper hollow portion slidably mounted in each said sleeve;
  - (d) a centrally located transverse support member extending between the sides of said main frame and carried by said frame; and
  - (e) elongated tension means having opposite end sections, each end section passing upwardly through the hollow upper portion of a leg member, through a sleeve, and terminally affixed to the upper end of said sleeve, said tension means further removably engaged by said transverse support, so that when said structure is in a supporting position said tension means transmits a counter-balancing force to said frame through said transverse support and said sleeves, and urging said legs into said sleeve.

2. The structure of claim 1 further comprising:

- (a) a mattress supporting inner frame mounted in said main frame, said inner frame having a hinged end portion;
- (b) a detachable elevation guide releasably secured to the end portion of said inner frame; and
- (c) a locking assembly secured to the main frame and coacting with said guide for fixing the end portion of said inner frame in a preselected position relative to said main frame and supporting said end portion, so that the end portion of said inner frame may be rotated about the hinge connection to a preselected position relative to the plane of the main frame and locked in said position to said main frame.

3. The structure of claim 1 further comprising:

- (a) a plurality of apertured lugs secured to said main frame; and
- (b) a second support means, having at least one leg member slidably mounted in said apertured lugs, for supporting articles above the plane of said main frame.

4. The structure of claim 3 wherein the support means comprises a tray having a plurality of leg members, said leg members mutually spaced a predetermined distance and slidably mounted in said apertured lugs.

5. The structure of claim 1 further comprising:

- (a) a mattress supporting inner frame mounted in said main frame, and carrying an end portion hingedly connected to said inner frame;
- (b) an arcuate channel releasably secured at an end thereof to the end portion of said inner frame;
- (c) an eccentric cam locking assembly secured to said main frame and registering on the interior of said

channel, said assembly having a disengaging lever connected to said cam, said cam normally urging said channel into said main frame, so that said cam coacts with said channel and frame to provide a friction lock, locking the end portion of said inner frame after said end is rotated about the hinge connection to a preselected position relative to the plane of the main frame.

6. The structure of claim 2 wherein:

- (a) the elevation guide comprises an arcuate channel having at least one hole extending through the base thereof, said channel releasably secured to the inner frame at an end thereof; and
- (b) the locking assembly comprises a stop secured to the main frame, an eccentric cam disposed within the channel and secured to the main frame, a locking pin mounted on the peripheral surface of said cam, said pin when in a locked position extending through a

5

hole in the channel, and resting on said stop said cam normally urging said channel against said main frame, and a disengaging lever mounted on said cam for rotating said cam away from said channel and said pin out of the hole.
